UNITED STATES PATENT OFFICE.

FREDERICK R. S. DITMARS, OF KANSAS CITY, MISSOURI.

STAMP-AFFIXING AND ENVELOP-SEALING MACHINE.

1,072,585.

Specification of Letters Patent.

Patented Sept. 9, 1913.

Application filed June 5, 1912. Serial No. 701,759.

To all whom it may concern:

Be it known that I, FREDERICK R. S. DITMARS, a citizen of the United States of America, residing at Kansas City, in the 5 county of Jackson and State of Missouri, have invented certain new and useful Improvements in Stamp-Affixing and Envelop-Sealing Machines; and I do hereby declare that the following is a full, clear, and exact 10 description of the invention, such as will enable others to make and use the same, reference being had to the accompanying drawings, forming a part of this specification.

The invention relates to the class of machines in which the operations of feeding and moistening the envelopes, affixing the stamps to the envelopes and sealing the envelopes, are successively performed, and is an improvement upon the stamp affixing and 20 envelop sealing machine for which Letters Patent were granted to me on the 22nd day of August, 1911, No. 1001001.

The objects of the present invention are, first, to dispense with the reciprocating 25 stamp supporting and feeding carriage and obtain the successive operative movements of feeding the stamps and affixing the stamps to the envelopes in a simplified, novel manner. Second, to proportion the feeding movement 30 of a stamp feeder to stamps or labels separable into different lengths. Third, to contract the length of stroke of the reciprocating bar actuating the stamp feeder. Fourth, to govern the rotating movements of the 35 main driving shaft automatically during the interval of time in which the feeding of the envelopes to the stamp affixing device has ceased. Fifth, to afford a positive feeding movement to the stamp feeder.

40 The invention consists in the novel construction and combination of parts such as will be first fully described and then specifically pointed out in the claims.

In the drawings, Figure 1, is a plan view of 45 an envelop moistening and sealing and stamp feeding and affixing machine embodying the invention. Fig. 2, is a longitudinal, vertical sectional view of the machine taken on the line x . x . on Fig. 1. Fig. 3, is a view in 50 elevation of a broken portion of the side of the machine upon the right-hand side and at its forward end, showing the main driving shaft and gear wheels, the envelop sealing rollers, the rotary shaft actuating the stamp feeder and affixer and the mechanism for

controlling the movement of the latter devices, when the specified number of envelopes have been stamped. Fig. 4, is a detail, vertical sectional view of the machine taken on the line y . y . on Fig. 1, showing the stamp 60 separating and affixing device and its position in dotted lines at the limit of its upward movement. Fig. 5, is a detail broken view of the T bar connecting the rear ends of the sides of the machine supporting 65 the crank shaft. Fig. 6, is a broken side view in detail of the depressed portion of the transverse bar supporting the forward ends of the slats forming the bed of the machine and connected with the left hand side of the 70 machine, showing a part end view of the stamp separator and affixer and the stamp supporting plate. Fig. 7, is a detail side view of the clutch on the shaft operating the stamp feeding and affixing devices, a 75 portion of the side being broken away to show the coiled spring. Fig. 8, is a vertical, sectional view of the gear wheel and clutch on the rotary shaft actuating the stamp feeding and affixing devices, taken on the line e . e . on Fig. 1. Fig. 9, is a detail broken view of the vertically positioned stamp supporting plate connected with the sides of the machine in rear of the rotary 80 shaft actuating the stamp feeding and affixing devices, the view being from the rear side of said plate, and upon the line z , z on Fig. 1, the flange on said plate being broken away. Fig. 9^a, is a detail vertical sectional view of the outer end of the reciprocating 85 bar to the stamp feeder. 90

Similar numerals of reference indicate corresponding parts in all the figures of the drawings.

The frame of the machine as seen in the 95 drawings to which reference is made, is rectangular in form and consists of the vertical side plates 10, 10¹, which are narrow in width and of the requisite length to support in successive order the envelop feeding, the 100 stamp feeding and affixing, and the envelop sealing mechanism. The sides 10 10¹ are supported by the legs 12 and 14 arranged at short distances inwardly from the respective forward and rear ends of the said sides 105 and are formed integral therewith.

The sides 10 10¹ of the frame are spaced apart a considerable distance to provide for the stamping of the various sizes of commercial envelopes, and are connected rigidly 110

together by means of the transverse forward and rear channel and I angle beams, 15 and 16 respectively. The ends of the forward channel beam 15, are connected by means of 5 the screws 17, with the inner surfaces of the downward extensions 18 of the lower portions of the sides 10 10¹ of the frame, which extensions form an integral part of the rear portions of the legs 12, supporting the 10 machine. The rear T angle beam is connected at its ends with the inner surfaces and upper portions of the rear legs 14, upon a line approximately horizontal with the forward transverse beam 15.

15 Portions 19, of the forward end of the side 10 10¹ of the frame of the machine, are extended upwardly a distance considerably in excess of the width of said sides, and in 20 said upward extensions is joined in a transverse direction to the machine the ends of a rotary shaft 20, actuating the stamp feeder and affixer, the position of the ends of which shaft are approximately in vertical lines with the forward surfaces of the legs 12. 25 One end of the shaft 20 extends through the upward extension 19, on the left hand side of the machine and a short distance outwardly from the line of the outer surface of said extension, and upon said end of the shaft is 30 a large gear wheel 21, which is loosely mounted on said shaft. Extending forwardly and horizontally from the portions 35 19, of the sides of the frame are the brackets 23, having vertical U shaped sockets 24, which are slightly below a line horizontal with the shaft 20.

Immediately below the brackets 23, are the forwardly extended brackets 25, which are also an integral part of the sides 10 10¹, 40 of the machine. In the brackets 25, is journaled upon a line horizontal with the lower surfaces of the side 10 10¹, and a short distance rearwardly from a vertical line extending through the sockets 24, of brackets 45 23, a large envelop sealing roller 26, the journal 27, upon which roller upon the left hand side of the machine extending a short distance beyond the line of the outer surface of said bracket and upon said journal is a 50 small gear wheel 28. In the U shaped sockets 24, on the brackets 23 is journaled a a gravity envelop sealing roller 29, which bears normally upon and is in contact with the surface of the envelop sealing roller 26, 55 these sealing rollers being the same as now employed by me for sealing the envelops and require no further description.

The bed or table over which the envelops are moved in the direction of the sealing 60 rollers consists of a series of longitudinally extending slats 30, arranged between the sides 10 10¹, at equal distances apart and extending at its forward ends from a position directly above the inner portions of the 65 feed roller 26, and in a horizontal line with

the principal portion of said roller, rearwardly to a position adjacent the rear end portions of said sides 10 10¹, of the machine.

The forward ends of the slats 30, are secured rigidly by screws 31, to the upper surface of a transverse supporting bar 32, secured at its ends by screws 33, to the inner surfaces of the forward portions of the sides 10 10¹, immediately in rear of the forward ends of slats 30. The rear ends of slats 30, 70 extend rearwardly to and are secured by the screws 36, to the upper surface of the transverse bar 35, which bar is secured at its ends to the inner surfaces of the sides 10 10¹ at 75 points on said sides approximately two-thirds the distance from the lines of the forward to the lines of the rear ends of said sides.

A portion of the bar 32, supporting the forward ends of the slats or bars 30, at a point a short distance inwardly from the line of the inner surface of the side 10 of the machine is bent at right angles at 37, and extended downward a short distance thence bent at right angles at 38, and extended at 39 horizontally and a short portion 40, bent at right angles and extended downwardly and connected rigidly with said inner surface of said side 10, thus forming a depressed portion of bar 32 as further explained. The forward end of the longitudinal slat or bar 30, adjacent the side 10, of the machine is made of increased width as at 31¹, (see Fig. 6) and extended to a position above the depressed portion 39 of 95 bar 32. 100

With the lower portion of the depressed portion 59, of the bar 32, is connected a casting 41, through which and the portion 39 of bar 32 extends an opening 42.

105 43 indicates a sliding bolt within the perforation 42, and connected at its upper end with the lower surface of the portion 31, of the slat 30. Upon the lower end of the bolt is a head 44, bearing upon the lower surface 110 of the casting. Extending around the bolt is a spiral spring 45, which bears upon the upper surface of the casting at its lower end, its upper end supporting yieldingly the forward end portion 31¹, of the slat 30, upon 115 which the portion of the envelop to which the stamp is affixed is supported. Immediately in rear of the transverse bar 35, supporting the rear ends of the slats or bars 30, 120 is a water receptacle or trough 46, which extends from the inner surface of the side 10 to the inner surface of the side 10¹, of the machine; the ends of the trough being connected rigidly with said sides, the upper edges of the trough being upon a line horizontally with the upper surface of the bar 35. In the trough 46, is a moistening roller 47, extending the length of the trough, the ends of the roller 47, being journaled in the respective ends of the trough. Extending 130

around the surface of the roller which is circular in cross section, is a covering 48, of suitable absorbent material which absorbs sufficient water in the trough to keep it in a moistened condition. Upon the side plate 10¹ of the machine, at a point forward of the position of the receptacle 46, and approximately intermediate the ends of said side plate 10¹, is an upward extension of said plate constituting a standard 49, with the outer portion of which is connected rigidly a water supply tank 50. With the lower end of this tank is connected one end of a water conducting pipe 51, the other end of which pipe extends to a position adjacent to the water receptacle 46, and is bent at right angles and extended within the receptacle through the adjacent end as seen in Fig. 1. In the pipe 51, is a cut-off valve 52.

53 indicates the moistening device for the surface of the envelops upon which the stamp is to be affixed and consists as seen of a frame, rectangular in form and open at both ends and in which is placed a sponge 54. The frame is located a slight distance above the upper surface of the slat 30, adjacent the side plate 10 of the machine and having the portion 31, and intermediate vertical lines passing through the forward end 30 of said portion 31, and the rear end of the slat 30, with which it is integral. The frame is supported by a bracket 55, secured to the upper surface of the side plate 10. A liquid supply pipe 56, is connected at one end with the lower portion of the tank 50, and the other end extended to a position above the sponge 54. In the pipe 56, is a fluid regulating valve 57.

Upon the inner surface of the side plates 10, 10¹ of the frame of the machine are the longitudinal track plates 58. These plates are located below the line of the horizontal surfaces of the slats 30, a distance equivalent to the thickness of an adjacent slat. These 45 track plates are narrow in width, one portion extending from a point on said sides above the line of the downward extension 18, of said side plates, rearwardly to the transverse bar 35, supporting the rear ends of 50 slats 30. Another portion 58¹, of said plates extends from the line of the rear surface of the ends of the water receptacle 46, to the line of the rear ends of the side plates 10, 10¹.

The forward movement to the envelops in 55 the direction of the forward end of the machine is produced by the reciprocal movements of a carriage frame 60, composed of transverse forward and rear bars or slats 61, 61^x and 62, which bars or slats are spaced 60 apart and the ends slidingly mounted on the track plates 58, and movable beneath the lower surfaces of the slats 30, and a transverse bar or slat 63, which is located at the rear end of the machine, and slidingly mounted on the rear end portions of the

track plates 58¹. With these transverse slats or bars 61, 61^x, 62 and 63 at points a slight distance inwardly from the lines of the inner surfaces of the side plates 10, 10¹, are connected the longitudinal slats or bars 64, 70 by means of the screws 64^x, the forward ends of which bars, which are connected with the transverse bars 61, extending in length from the lines of the rear ends of sides 10 10¹, forwardly to a point about three-fourths the distance to the line of the forward end of the machine; the transverse bar 62, approaching to within a short distance of the transverse bar 35, at the limit of rearward movement of the frame 60. Upon the upper surface of bar 62, are feedblocks 66, the upper surfaces of which are rearwardly inclined and with which the unsealed flaps of the envelops come first into contact. These blocks are placed in position adjacent the 80 longitudinal surfaces of the stationary slats 30. Upon the upper surface of the transverse bar 61, of frame 60, are feed blocks 67, which are in line in the longitudinal direction of the machine with the feed blocks 66, 85 and the upper surfaces of the blocks 67 are rearwardly inclined in a slightly less degree. To the upper surface and rear ends of the bars 64 are connected the ends of a transverse envelop supporting plate 65, the forward end of which plate is curved upwardly at 65^x in a slight degree so as to engage with the sealing flaps of the envelops. Upon the lower surface of said portion 65, is a pad of absorbent material 65°, which comes into contact with the moistening surface of the roller 47. Upon the left hand side of the machine and upon the side plate 10¹, in a line transverse to the standard 67, supporting the tank 50 is a standard 68, integral 90 with the side plate 10¹.

With the inner surfaces and upper end portions of the standards 49 and 68, are connected the respective ends of a transverse bar 69, which ends are bent at right angles 110 at 70, and connected rigidly with said standards. In the said bent portions 70, of the bar 69, are journaled the ends of a rock shaft 71, upon which shaft are secured by the screws 72, the sleeves 73, with which sleeves are connected one end of the finger bars 74, the lower ends of which finger bars extend forwardly and downwardly at an angle to the bars or slats 30, forming the bed of the machine. Upon the lower ends 115 of the finger bars 74, are pivots 75, extending at right angles thereto and upon said pivots are mounted the rollers 76, which are composed of elastic materials, such as india rubber, and which bear on the upper surface of the slats 30. Around the rock shaft 71, are coiled the spring wires 77, one end of which coil of the respective wires is extended rearwardly upon the upper surface 120 of the transverse bar 69, and the other end 125 130

extended forwardly and bent at right angles at 78, and extended through the finger bar 74, at a point between the ends of said finger bar.

5 Directly beneath the lower surface of the transverse bar 69, is a roller 79, the ends of which are journaled on the respective standards, 49 and 68, between which roller and the upper surface of the slat 30, is formed a 10 space or throat through which the envelope first pass, guided by the roller 79. At a point on the side plates 10, 10¹, of the frame of the machine, approximately one-third the distance rearwardly from the upward extensions 15 of the side plates 10, 10¹, of the frame of the machine in the direction of the standards 49 and 68, are standards 80, extending in height, a short distance above the lines of the upper ends of said standards. 20 In the upper end portions of the standards 80, are journaled the respective ends of a rock shaft 81, the end of which shaft, in the left hand side of the machine, is extended through the standard 80, upon said side 10¹, of the machine and upon said end of the shaft is connected rigidly, a brake arm 82, the outer end of which arm extends downwardly to the line of the lower surface of said side plate 10. Upon the rock shaft 81, 30 are a number of sleeves 83, secured fixedly to said shaft, with which sleeves are rigidly connected the upper ends of the finger bars 84, the lower ends of which bars extend forwardly and downwardly and bear upon the upper surfaces of the respective slats or bars 30, located inwardly from the slats or bars adjacent to the side plates 10 10¹.

With the inner surfaces of the standards 80, at points a short distance downwardly 40 from the lines of their upper ends, is connected rigidly the respective ends of a transverse bar 85, the rear surfaces of the bar being upon a line with the rear vertical surfaces of the standards.

45 In the standards 80, immediately forward of the bar 85, is journaled a rock shaft 86, upon which are a number of sleeves 87, secured rigidly to said shaft in like manner as the sleeves 73, on shaft 71. Connected at 50 one end rigidly with the sleeves 87, are fingers 88, extending forwardly and downwardly and provided with pivots 89, upon which are mounted the small rollers 89^x, which bear upon the upper surfaces of the 55 slats or bars 30, of the bed of the machine, alternately to the slats upon which the fingers 84, on shaft 81, are arranged to bear.

90 indicates the main rotary driving shaft of the machine, which extends in a transverse direction to the sides 10 10¹, of the frame of the machine, the ends of which shaft are journaled in the downward extension 18, of said sides in a vertical line with the forward legs 12, supporting the machine 65 and a short distance forward and in a hori-

zontal plane with the channel beam 15, connected with the said portions 18, of the side plates 10 10¹. The end of shaft 90, on the left hand side of the machine, extends through the side 10¹ of the frame of the machine and upon said end is a large gear wheel 91, which meshes with the gear wheels 21 and 28. Upon said end of the shaft 90, is a crank arm 90^x. Upon the shaft 90 intermediate the ends is a bevel gear 91^x. 70 75

92 indicates a longitudinally extended rotary power shaft, its forward end being extended through the channel beam 15, in the direction of and a short distance from the shaft 90, upon which end of the shaft is a 80 bevel gear wheel 93, which meshes with the bevel gear wheel 91^x, on shaft 90. The rear end of the shaft 92, extends rearwardly to the rear transverse connecting I angle beam 16, to the side plates 10, 10¹, and upon which beam is a boss 94, in the inner side of which boss is an opening or seat 95, in which the rear end of shaft 92, is journaled. Upon said rear end of shaft 92, is a bevel gear wheel 96. Extending in a vertical direction 90 through the I beam 16, and the boss 94, is a crank shaft 97, upon the lower end of which shaft adjacent the lower portion of boss 94, is secured a bevel gear wheel 98, which meshes with the bevel gear wheel 96, on 95 shaft 92. Upon the upper end of shaft 97, is a crank arm 99, of considerable length, with the outer end of which arm is pivotally connected at 100, the rear end of a rod or bar 101, the forward end of which bar extends forwardly in an upwardly inclined direction to and its extreme end is bent horizontally in position and pivotally connected at 102, with the lower surface of the forward transverse bar 61, of the reciprocating 100 carriage frame 60. 105

With the rear portions of the upward extensions 19, of the side plates 10 10¹ at the forward end of the machine are rigidly connected the forwardly extended angular ends 110 103, of a transverse stamp supporting plate 104, which angular portions 103, are joined to a shoulder 105, formed on the inner surfaces of said plates 19. The lower portion of the stamp plate 104, extends downwardly 115 to within a short distance above the line of the upper surfaces of the slats 30, and with the lower surface of which plate is connected the inner portion of a longitudinally extended stamp supporting plate 106, which is 120 of a width slightly in excess of the width of a single stamp, and which plate extends from a position approximately to a vertical line extending through the inner portion of the slat 30, adjacent to the side plate 10¹, of the main frame of the machine, to a position in a vertical line with the inner edge of the broad portion 31, of the slat 30, 125 which is adjacent the side plate 10, of the frame of the machine. Upon the outer lon- 130

itudinal portion of the stamp supporting plate 106, is an upwardly extended stamp guiding flange 107.

108, indicates a stamp supporting roller 5 spool which is pivotally connected with the rear surface of the stamp plate 104, at a point directly above the end portions of the plate 106, adjacent the side plate 10, of the frame of the machine. Upon this spool is 10 wound a narrow strip of stamped paper 108^x, of the desired length and having an adhesive substance upon one of its sides. This stamped paper is without the transverse perforation common to the lines of 15 separation of a stamp for commercial uses, but may be perforated when desired and the separation made by the stamp affixing plate for different lengths of stamps or labels to which the invention is particularly adapted, 20 the strip being wound on the spool 108, with the adhesive side inward. Beneath the roller or spool 108, and positioned in the direction of the side 10 of the frame of the machine from a vertical line extending 25 through the stamp roller are the guide rollers 109, and 110, and in close contact with each other. Secured fixedly to the lower portion of the stamp plate 104, is a stamp guiding plate 112, which extends from the 30 roller 109, above the plate 106, to a position one-third the length of plate 106, inwardly from the end in the direction of the side plate 10¹, of the frame of the machine. Upon the lower portion of plate 112, is an 35 outwardly extended guiding plate 114, the end in the direction of the roller 109, being curved upwardly at 113, the lower surface of said portion 113, being opposite the point of contact of the peripheries of the two 40 stamp guiding rollers 109 and 110, and the space between the lower surface of plate 114, and the upper surface of plate 106, being sufficient to permit the passage of the strips of stamped paper.

45 The stamp feeding devices consist of a rectangular flat plate 115, upon the lower surface of which is a sheet of elastic material 116, such as india rubber or other equivalent substances. With the lower portion 50 of plate 115, are connected the upper ends of a series of needles or pins 117, the pointed lower ends of which needles extend through the elastic sheet and a slight distance below the line of the lower surface of said elastic 55 sheet.

With the upper surface of plate 115, upon a line with its rear or inner edge is connected a vertical plate 118, its upper end being curved in the arc of a circle. Upon the upper surface of plate 115, in a central position outwardly from plate 118, are the lugs 119, between which lugs is extended one end of a reciprocating bar 120, pivoted thereto at 121. The outer end of the bar 120, is extended in the direction of the side plate 10¹

of the frame of the machine to a point above the guide plate 112. A short distance from a vertical line extending through the curved end portion 113, of said plate, in the outer end of bar 120 is a longitudinally extended 70 opening 122.

123, indicates a crank shaft which is short in length and one end extends through the stamp plate 104, in the direction of and in the same horizontal plane as the shaft 20, and upon said end is a bevel gear wheel 124. On the shaft 20, is a bevel gear wheel 125, with which the bevel gear wheel 124 is in mesh. Upon the outer end of shaft 123, is a crank arm 126, which is rotatable adjacent to the rear surface of the stamp plate 104. Upon the outer end of the crank arm is secured the crank pin, 127.

Extending in the longitudinal direction of and within the outer end of the reciprocating bar 120, is a screw threaded opening 128, which communicates with the opening 122. In the said opening 128, is an adjusting screw 129, the inner end of which screw bears against a ring 130, extending loosely around the crank pin. Upon the outer end of the screw is a head 131. To the inner surface of the stamp plate 104, a short distance from the plate 118, of the stamp feeder in the direction of the crank shaft, is secured by 85 the screw 133, a vertical plate 132, having an outwardly extended lower portion 134, which extends beneath the line of the lower surface of the reciprocating bar 120. In the plate 132, is a vertical slot 135, through 90 which the fastening screw 133, extends. In the lower portion of the reciprocating bar at a point a short distance from its pivotal end portion and above the plate 134, when the feeder plate is in its retracted position, 95 is a notch 136, slightly wider than said plate 134.

137 indicates a depressing bar for the stamp feeder which is rigidly connected thereto at 138, near the longitudinal side portion of the stamp plate 115, the outer end extending in the direction of the guide roller 110. A spring wire 137^x is secured at one end to the outer surface of the plate 107, which extends along the outer side of the said bar is thence bent inwardly and hooked over the upper surface of the said bar 137.

For the purpose of controlling the action of shaft 20, when the envelopes to be stamped have passed through the machine upon the portion of shaft 20, extending outwardly from the line of the outer surface of the side plate 10¹, is a circular clutch wheel 141, having a hub 142, which extends inwardly past the line of the inner surface of side plate 10¹ and is secured to the said shaft by a screw threaded pin 143. In the outer face of the clutch wheel is a wide groove 144, extending diametrically through the said 125 130

wheel in which groove is a sliding clutch plate 145, one end of which plate extends normally a short distance past the line of the periphery of said plate and is curved or rounded at 146. In the central portion of the plate 145, is a longitudinal slot 147, through which shaft 20, extends and between which shaft and the end of the slot in the direction of the outwardly extended end 146, is a spiral spring 148, one end of which spring bears on a sleeve 147^x, loosely mounted on the said shaft and the other end against the said end of the slot. Upon the outer face of the circular clutch plate 141, is a circular covering plate 149, secured by screws 149^x, to said plate. Upon the other end of the clutch plate 145, from that having the extended rounded end 146, is an outwardly extended plate 150, having an upwardly extended outer flange 151. The gear wheel 21 which is loosely mounted on shaft 20 is held thereon by a circular collar 152, secured to the outer end of the shaft 20, by means of a pin 153. Upon the inner side of the gear wheel 21, is a hub 154, and upon said hub is a pin 155, extending radially therefrom and to a point in which the outer end of the pin comes into contact with the plate 150, on the clutch bar 145.

30 156 indicates the self acting clutch operating brake bar which consists of a strip of Bessemer steel twisted and secured by the screw 157, to the outer surface of the side 10¹, of the frame of the machine and a short distance in rear of a vertical line extending through the standard 80, supporting the crank arm 84, and retractive into the position seen on dotted line in Fig. 3. From the line of end 158, the brake plate extends forwardly and in a horizontal line to a point a slight distance in rear of the line of the upward extension 19, of the side 10¹ of the machine and is then bent at right angles and a portion 159, is extended upwardly to a point horizontal with the upper periphery portion of the clutch wheel and a short portion 160, extended in the direction of and a slight distance beyond the upper peripheral portion of the said clutch wheel and in the path of rotation of the rounded end 146, of the sliding clutch plate 145, the normal position of said portion of the brake bar, and the portion 160, being seen in solid lines in Fig. 3. Upon the upper surface of the horizontal portion of the brake bar the inner end of the brake arm 82, on the shaft 81, is in frictional contact.

40 45 50 55 60 65 70 75 80 85 90 95 100 105 110 115 120 125 130

Extending through the stamp plate 104, upon a vertical line extending past the inner edge of the broad plate 31¹, of the slat 30, adjacent to the side plate 10, of the machine, is a vertical opening 161, extending through the central and lower portion thereof. Upon the forward surface of the stamp plate 104, is a bracket 162, extending forwardly from

the line of the upper surface of said plate and attached thereto in a position to one side of a vertical line passing through the opening 161. Upon the outer end of the bracket is a downward extension 163.

70 75 80 85 90 95 100 105 110 115 120 125 130

The stamp separator and affixer consists of a plate or casting 164, of considerable thickness, rectangular in form and approximately the same width as that of the portion 31¹, of the slat 30, which extends beneath said plate. The surface of the plate in the direction of the end of the stamp supporting plate 106, is in vertical lines and terminates at the line of the lower surface of the plate in a cutting edge 165. With the upper surface of the plate 164, is connected integrally an arm 166, which extends forwardly through the opening 161, in the stamp plate at an angle to said plate, its outer end extending beneath the line of shaft 20, and from thence extended partially around said shaft and rearwardly in the direction of the stamp plate, forming a U shaped portion 167. This curved or U shaped portion of the arm 166, is pivotally connected at 169, to the adjacent portion and lower end of the downward extension 163 of the bracket 162, on the stamp plate 104. Upon the shaft 20, is a heart shaped cam 170, which is fitted within the inner surface of the sides of the U shaped portion 167, of the arm 166, in such a manner as to impart an upward and downward movement to the stamp affixing plate 164, and afford an interval of time or rest when the limit of movement is reached in both upward and downward movements of the plate.

95 100 105 110 115 120 125 130

In the operation of the machine the envelops to be stamped are placed collectively upon the upper surface of the plate 65, upon the rear ends of the side bars 64, of the reciprocating carriage 60, with the adhesive sealing surfaces of the sealing flaps of the envelops positioned downwardly and extended forwardly upon said plate. Water is supplied from the tank 50, to the trough 46, carrying the roller 47, and also the sponge 54, in the sponge supporting frame 53, and the free end of the stamp paper 108^x, is extended beneath the stamp feeder plate 115. Power being applied to the crank arm 90^x on the main driving shaft 90 rotation is imparted thereto, which motion is transmitted through the bevel gear wheels 91^x and 93, on the respective shafts 90 and 92, and the bevel gear wheels 96, and 98, in the said shaft 92, and the crank shaft 97, respectively and a reciprocating movement is imparted to the carriage frame 60. During this initial movement of the carriage frame the position of the brake plate 156, governing the movement of the rotary shaft 20, and the stamp feeding and affixing devices actuated thereby is as seen in full lines in Fig. 3. The arm 82, on the rock shaft 81,

acting to hold the portion 160, of the brake bar in contact with the periphery of the clutch wheel the said portion 160, of the brake plate, consequently being on the path 5 of the rounded end portion 146, of the clutch bar 145, and moving the portion 160, on the said clutch bar into the position seen in dotted lines in Fig. 8, and out of line with the pin 155, on the hub 154, of the gear wheel 21, consequently the shaft 20, is inactive while the gear wheel 21, is free to rotate with the gear wheel 91.

The envelops are now fed one at a time from the bottom of the assembled number 15 of envelops, the sealing flaps being placed slightly in advance of the upwardly curved portion 65^x, of the plate 65, carrying the pad 65°, and upon reaching said point the sealing flap turns downwardly in the direction 20 of the pad 65°, from its own tendency to fold and is moved forwardly beneath the gear roller 79, in the throat beneath the said roller and the slats 30, the adhesive surface of the flap becoming moistened from the 25 pad 65°, which receives its moisture in passing over the moistening surface 48, of the roller 47, in the trough 46. Upon this forward movement of the envelop the moistened flap portion of the envelop is fed beneath the rollers 76, on the rock shaft 71, and which rollers retain the envelop from 30 movement upon the upper surface of the slats 30, during the time a reverse movement is made rearwardly of the reciprocating carriage 35 60, in which movement the feed blocks 66, on the reciprocating carriage 60, move beneath and in rear of the envelop and upon the next forward movement of the reciprocating carriage the feed blocks 66, come into 40 contact with the rear longitudinal portion of the envelop and move the envelop forward in the direction of the fingers 84, on the rock shaft 81, controlling the brake arm 82, and the rollers 89^x, on the rock shaft 86, 45 at the same time the upper surface and right hand end portion of the envelop is moved beneath the moistening sponge 54. Upon reaching the fingers 84, on the rock shaft 81, the forward portion of the envelop contacts therewith and raises the fingers upwardly 50 from the surface of the slats 30, and at the same time moves the end of the brake arm 82, forwardly and upwardly from the horizontal portion of the brake plate which retracts rearwardly into the position seen on dotted lines in Fig. 2, and out of contact 55 with the clutch plate 145. This action follows the action of spring 147, which acts to move the portion 160, of the brake plate into the position seen in Fig. 2. The pin 55, on 60 wheel 21, engaging with the plate on the clutch wheel and the portion 160, of the brake plate acting by gravity on the clutch wheel. The envelop being now held by the rollers 89, during the rearward movement 65

of the reciprocating carriage 60, the forward feed blocks 67 pass beneath and in rear of the envelop and upon the succeeding forward movement of the feed blocks 67, the envelop is moved beneath the plate 106, 70 carrying the strip of stamped paper, the right hand moistened end of which envelop is in position upon the upper surface of the broad portion 31^x, of the slat 30, adjacent the right hand side of the machine and beneath the stamp affixing plate 164, which is now in an upward position as seen in dotted lines in Fig. 4.

At the beginning of the forward movement of the reciprocating carriage 60, the 80 crank arm 99, on the crank shaft 97, which acts to move the carriage forwardly is extended rearwardly and is upon a dead center in respect to its circle of rotation—the crank arm 90^x, upon the main driving shaft 90, being in an upwardly extended vertical position the envelop being engaged by the forward feed blocks 67, as described. Upon the movement of the crank arm 90^x, to the right in a half circle of rotation—the gear 90 wheel 91 on the main driving shaft 90, moves the gear wheel 21, the same distance imparting rotation in one half of a circle to the crank 126, actuating the feed plate 115, on the reciprocating carriage 60, and said plate moves in the direction of the plate 31^x, on the slat 30, of the bed of the machine, the pins 117 on the feed plate engaging with the free end of the strip of stamp paper which extends thereunder and the said portion of the stamp paper is moved a distance corresponding to the length of a single stamp upon the upper surface of the broad portion 31^x, of the slat 30, and beneath the stamp affixing plate 164, which is in an elevated position as seen in dotted lines in 95 Fig. 4.

In the forward position of the feed plate 115 the reciprocating bar 120 is fulcrumed upon the outward extension 134 of the plate 110 132. In the rearward movement of the bar 120 the downward movement of the crank arm 126 depresses the inner end of the bar until the stamp feed plate 115 is raised from and to a position above the 115 stamp paper, and the bar 120 moves backwardly actuated by the crank arm until the notch 136 comes opposite the extension or fulcrum 134, when the feed plate 115 drops upon the stamp paper in readiness for a 120 forward movement. In these forward and rear movements of the plate 115 the depressing bar 137 acts to keep the feed plate 115 from a rocking movement and retains the same in a uniformly horizontal position, 125 the spring wire 137^x keeping said bar pressed upon the plate 115. The plate 135 may be adjusted to let the feed plate 115 (when the notch in the bar 120 approaches the fulcrum 134) fall heavily upon the 130

stamp paper this adjustment being obviously downward. The cam 170, which is holding the stamp affixing plate 164, in an elevated position in the same movement of 5 the crank arm 90°, passes the upper terminal portion of the U-shaped member 167, of the arm 166, and descends with an accelerated movement as this action of the cam leaves a space between the narrow portion 10 of the cam and the inner surface of said terminal portion of the U shaped member 167, in which movement the stamp affixing plate 164, moves downwardly the cutting edge 165, separating the stamp from the 15 strip of stamped paper, the cam now acting upon the upper surface of the arm 166, affixing thereby the stamp to the moistened surface of the envelop, during a slight interval or rest of the stamp affixing plate in 20 which the cam acts to compress the stamp upon the envelop. In the next half circle of rotation of the crank arm 90°, the cam 170, raises the stamp affixing plate gradually in an upward direction, the envelop feeding 25 carriage in the meantime moving forward and forcing the envelop between the sealing rollers 26, and 29, the former being actuated by the gear wheel 91, which rollers seal the moistened flap and ejects the envelop from the machine. In the next quarter 30 of a circle of rotation of the arm 90°, the said arm comes into an upwardly extended vertical position, and the envelop feeding carriage 60 moves rearwardly in position, the cam 170, holding the stamp affixing plate 164, elevated in position during 35 the next movement of the crank arm 90°, in its half circle of rotation during which time carriage 60, again moves forward bringing forward the envelops in 40 succession to be stamped in like manner as described, of the first envelop. Upon the passage of the last envelop to be stamped past the fingers 84, which are held by the successive envelops in a raised position 45 these fingers drop upon the slats 30, thus permitting the brake arm 82, to fall and at the time the end 160, of the brake bar is in frictional contact with the clutch wheel 141, 50 to move into a vertical position and hold the brake bar from movement so that when the rounded portion 146, of said bar contacts with the portion 160, of said bar the clutch bar moves inwardly compressing the 55 spring 147, and consequently leaving the gear wheel 21, free to rotate independent of shaft 20.

In order to meet the requirements of a 60 change in length of the stamp and especially in the affixing of labels such as is used with a printed address, the screw 129, in the reciprocated bar 120, may be turned so as to lengthen or shorten the distance between the crank pin 127, and the crank shaft 123, 65 increasing or decreasing the lost motion in

the stroke necessary for moving the stamped strip beneath the stamp affixing plate 164. The main driving shaft may be operated by other than manual power when desired and such modifications employed as are 70 within the scope of the appended claims.

Having fully described my invention, what I now claim as new and desire to secure by Letters Patent is:—

1. In a stamp affixing machine for envelops, the combination with a suitable support upon said machine of a rotary shaft, a stamp affixing device actuated thereby, a cam on said shaft, an arm on said stamp affixing device having a U shaped portion pivotally connected with the said support within which the said cam is adapted to rotate. 75

2. In a stamp affixing machine for envelops, the combination with the frame of the machine, a transverse vertically positioned supporting plate, connected at its ends with the respective sides of said frame, having a vertical transverse opening therein, a rotary power shaft journaled at its respective ends in the sides of said frame adjacent to the forward surface of said supporting plate, means for imparting rotation to said shaft, and a stamp affixing plate adjacent to the rear surface of said vertical supporting plate, a bracket on the forward surface of said plate adjacent the vertical opening therein, an arm connected with the said stamp affixing plate, extending in an upwardly inclined plane through said vertical opening, and having a U shaped terminal portion upon its upper end pivotally connected with said bracket, and a heart shaped cam on the said rotary shaft within the U shaped terminal portion of the said arm. 85 90 95

3. In a stamp affixing machine for envelops the combination with the stamp separating and affixing device, of a stamp feeder, a reciprocating feeder operating bar, a crank shaft, an arm on said shaft, and a crank pin operating the said bar and controlling means on said reciprocating bar at one end of the said bar acting to control the movement of the crank pin in said slot. 100 105 110

4. In a stamp affixing machine the combination with the frame of the machine, and with the vertically operable stamp separating and affixing devices, of a transverse vertically positioned plate connected at its ends with the sides of said frame, a horizontal stamp supporting guiding plate for the strip of stamp paper connected with the side of said vertically positioned plate, and extending to a point adjacent the path of movement of the stamp separating and affixing devices, a rotary crank shaft extending through said vertically positioned plate, an arm on said shaft, means for operating said shaft, and a bar connected at its inner 115 120 125 130

end with said arm an outwardly extended fulcrum plate on the vertically positioned plate supporting said bar, a reciprocating stamp feed plate, movable upon the stamp supporting and guiding plate, connected with the forward end of said bar, and an elastic pad on the lower surface of said stamp feed plate.

5. In a stamp affixing machine the combination with the main frame, a rotary crank shaft mounted upon said frame, a crank on said shaft, a reciprocating feeder plate, a bar pivotally connected with said plate and actuated by said crank and controlling 10 means acting upon the feeder plate to prevent a rocking movement of the said feeder plate.

6. In a stamp affixing machine for envelops, the combination with the frame of 20 the machine and the stamp affixing devices on said frame, of a transverse vertically positioned plate connected at its ends with the sides of said frame and a horizontal plate supported thereby upon which a strip of 25 stamped material is movable in the direction of the stamp affixing devices, a rotary crank shaft and arm supported by said vertical plate, a stamp feeding plate, a reciprocating bar pivotally connected at one end with the 30 stamp feeding plate and at the other end with the crank arm on the crank shaft and a spring controlled bar connected at its forward end with the stamp feeding plate and having its free end movable upon the upper 35 surface of the horizontal plate supporting the stamped material and acting to preserve a normal horizontal position of the stamp feeder plate.

7. In a stamp affixing machine for envelops, the combination with the frame of 40 the machine of a transverse vertically positioned plate connected at its ends with the sides of said frame, a horizontal plate upon the rear surface of the said plate supporting 45 the strip of stamped material, a stamp feeding plate movable on the supporting plate for the strip of stamped material, a reciprocating bar pivotally connected with the stamp feeding plate and a guiding bar rigidly connected with the stamp feeding plate, and having its free end movable upon the supporting plate for the stamped material and a spring wire slidably connected with the said guiding bar, and fixedly connected 50 with the supporting plate for the stamped material.

8. In a stamp affixing machine the combination with the frame of the machine and the stamp affixing devices of a transverse 60 vertically positioned plate connected at its ends with the sides of said frame, a horizontal plate on the rear surface of the said plate supporting the strip of stamp material, a crank shaft extending through the said vertically positioned plate and an arm on said

shaft means for operating the crank shaft and a stamp feed plate movable on the supporting plate for the stamp material, a reciprocating bar pivotally connected with the said stamp feeding plate at its forward end and with the arm on the crank shaft at its inner end, an outwardly extended fulcrum plate for said bar on the said vertically positioned plate, said bar having a notch in its lower surface at the limit of its rearward movement.

9. A mechanism for stamp affixing machines for envelops, comprising a rotary driven shaft, a gear wheel loosely mounted on said shaft, and a hub on said wheel, a clutch upon said shaft adapted to clutch the hub of said loose wheel, a gravity clutch releasing pivoted brake bar, a rock shaft, fingers on said shaft and a brake arm on said shaft whose free end engages with the upper surface of the brake bar.

10. In a stamp affixing machine for envelops, the combination with the frame of the machine and the main driving shaft of an independent rotary shaft, an envelop feeding reciprocating carriage actuated by the main driving shaft, stamp feeding and stamp affixing devices, actuated by said independent rotary shaft, a loosely mounted gear wheel on the end of said independent shaft and a fixed gear wheel having a hub on the main power shaft meshing with said loosely mounted gear wheel, a clutch wheel on said independent shaft and a spring actuated clutch bar on said wheel and a clutch plate on the inner end of said bar, a pin on the hub of the loose gear wheel, which wheel the clutch plate is adapted to engage in rotation, a rock shaft mounted on the sides of the said frame and fingers on said shaft, a gravity brake plate pivoted at its inner end to the side of the machine and having a bent portion adapted to move over the surface of the clutch wheel in the path of the clutch bar and a brake arm on the rock shaft adapted to engage with the upper surface of the gravity brake bar and control its movement.

11. In a stamp affixing machine for envelops, the combination with the frame of the machine and with the main power shaft of a reciprocating stamp feeding carriage actuated thereby, an independent rotary shaft upon said frame and a loose gear wheel having a hub mounted on said shaft, stamp affixing devices actuated by the said independent shaft and to which the envelops are moved successively by the stamp feeding carriage, a clutch wheel on said independent shaft and spring actuated clutch bar, a clutch plate on the inner end of the clutch bar and a pin on the hub of said loose gear wheel with which the clutch plate normally engages, a fixed gear wheel on the main driving shaft, meshing with the loose
